CONTRIVANCE FOR REVERSING THE DIRECTION TAKEN BY GAS OF REGENERATIVE COKE OVENS

Paul Van Ackeren, Essen-Ruhr, Germany, assignee, by mesne assignments, to The Koppers Company of Delaware, Pittsburgh, Pa., a corporation of Delaware

Application August 17, 1931, Serial No. 557,624
In Germany August 18, 1930

2 Claims. (Cl. 277—5)

The invention relates to contrivances for reversing the direction taken by gas in the case of ovens heated by gas or air preheated by regenerators and especially of ovens constructed for the production of gas and coke, and more particularly to reversing contrivances in the construction of ovens provided with regenerators, which are heated by lean gas, for example producer gas.

In the working of ovens with regenerators, it is usual to periodically change the direction of flow of the heating gases and the air on the one hand and the waste gases on the other hand within the oven. For this purpose, there are inserted valves in the connecting pipe lines between the regenerator, on the one hand, and the waste gas channel and the gas channel, on the other hand, which are preferably provided in a contrivance generally known by the name of "knee piece" which is also provided, should the respective regenerators also be intended to serve alternatively for preheating the air, with an extra valve for inflow of air, which latter is controlled by a connection on the interior of the knee piece to control communication with the outside air.

It is already known, that in the running of ovens with regenerators especially coke ovens, the valves in the knee piece when the heating is reversed, have a distinct sequence, in order to avoid in the interior of the oven any losses of gas or possibly the formation of a mixture of air and gas, which is explosive.

This sequence can be more easily understood by reference to a coke oven with regenerators, which is fitted up with groups of four regenerators each, of which, in each working period, one serves for the preheating of lean gas, one for the preheating of the air, whereas in the same period the other two regenerators are heated by the passing through of the waste gases. In this case, two regenerators on one side of a group are connected up, each by one knee piece, one with the lean gas pipe line and the other with the outer air, respectively. The two regenerators on the other side of the group are connected, each by one knee piece, with the waste heat channels. The openings to the waste heat channels, on the one hand, and the openings of the air and gas inlet pipe lines into the knee piece, on the other hand, are controlled by the valves provided therefor, which, preferably from outside of each knee piece, are worked by a special contrivance, which is connected up in turn with a common adjusting contrivance for all the valve operating mechanisms.

In one regenerator period, the valve for controlling the lean gas in one knee piece is opened

and the waste gas valve controlling the opening to the waste gas channel, is closed, whereas in the neighbouring knee piece, which is connected with the regenerator for the air, the air valve is open and the waste gas valve is closed. In the two knee pieces through which the waste gases pass, the air and lean gas valves are closed and, on the other hand, the waste gas valves are opened. When, during the running of the plant, it is required to change the direction of the heating in the heating flues of the coke ovens, then first of all the gas valve through which the lean gas is passing must be closed. After this has been done, simultaneously the air valve has to be closed in the knee piece which up to then has been filled with air, and the waste gas valve has to be opened; furthermore, the knee piece through which, up to the present, the waste gases have passed and through which the air is to be led during the following working period, must have its waste gas valve closed and its air valve opened and furthermore, simultaneously during these adjustments, the waste heat valve is opened in the knee piece through which the lean gas formerly passed, and the waste heat valve closed in the knee piece through which, in the next working period, the lean gas is to pass. After the termination of the simultaneously effected reversing of the air and waste heat valves, the gas valve is to be opened in the knee piece through which, during the following period, the lean gas is to pass. In this manner, in all of the knee pieces, which is necessary to obtain the desired reversal in direction of flow of heating gas for the heating of the oven, is attained.

To bring about the desired sequence of movements, which is comparatively complicated during the reversing of the gas-, air- and waste heat valves in the knee pieces, the arrangement for governing the individual valves up to the present time comprised various pulling arrangements, and special wire ropes and the necessary winches had to be arranged to connect up all the gas, air, and waste heat valves, with a rope winch, provided at the top end of the battery. Moreover, the working of the air and waste heat valves has been effected by means of a common rope and a common rope winch, to adjust the same as already described and achieve simultaneously the reversing of the heating arrangement.

Up to the present, for the working of the rope winches one proceeded in the following manner, a workman sets each one in action one after the other. This process is, however, disadvantageous in as much as one has thus been compelled to rely

simply on the trustworthiness of the workmen in question, in respect of the regularity of the reversal as well as the exact carrying out of the sequence of the adjustment of the valves.

5 It had been proposed indeed to bring the driving contrivances for the various adjustments of the winches into connection with a guiding gear, in which event the various rope winches were to be set in action in the desired sequence by one 10 single driving organism. Such guiding and driving arrangements prove, however, in their construction to be exceedingly complicated and expensive and are very sensitive to outside influences, which in the case of the comparatively 15 rough working in the running of a coking plant represent a great disadvantage.

For this purpose according to the invention there is arranged between the common pulling contrivance for all the knee pieces and/or an adjusting lever linked up with the pulling contrivance on the one hand and the valve on the other hand, a pulling organism which, in one moving direction, has a stiff connection between the valve and the pulling organism and by the other moving direction permits of a yieldable connection by which means are provided, so that the length of the connecting pieces between each single valve and the gripping point of the pulling rope can be adjusted.

20 30 There are quite a number of possibilities for carrying out the cardinal features of the inventive idea.

The object of the invention is, furthermore, to achieve a special distribution of the connecting 35 links between the gas, air and waste gas valves and the working arrangements belonging to the knee piece therefor. According to the invention, there rests on the knee piece a working shaft connected by a lever with the reversing chain or 40 the like, which shaft is fitted up with various arms, connected each with one of the valves in the knee piece by a pulling arrangement yieldable in one direction. According to the invention, the pulling organism consists preferably, of one yieldable in one direction, in a piston sliding in a tube 45 extension of the valve shaft of which the piston rod is connected with a lever belonging to the working shaft by means of a chain or an equivalent pull arrangement, in which the length of 50 this connecting chain can be modified by suitable means, for example by adjusting screws provided on the lever of the working shaft. In the case of this contrivance the tubelike extension of the valve shaft is closed at its upper end by a cap, 55 and the piston fitted in the interior of the shaft extension is so placed that it may move upwards against the lower side of the cap and so that on further raising the piston against the cap the valve belonging to it, is taken along with it.

60 In many cases it may be of advantage to employ, instead of the working shaft equalizing piston in a tubelike extension of the valve shaft, essentially the connecting chain or another yieldable pulling organism between the raising arm of 65 the lever of the working shaft and the valve and a connecting piece yieldable in one direction of the said two organisms.

Further objects of the present invention concern the use of the novel knee pieces of the ovens 70 heated by gas or air preheated by regenerators for the production of gas and coke and the means in connection with same to preserve the heating sequence i. e. the reversing of the valves in changing over of the direction of flow of the heating 75 gas.

With these and other objects of the invention in view I will now describe a preferred construction of the invention shown on the accompanying drawings.

On the drawings there is shown in Figure 1 a 5 vertical section of the knee piece formed according to the invention viz. on the line I—I of the Figure 4.

Fig. 2 is a side view and Fig. 3 an upper view 10 of the knee piece of Figure 1.

Figure 4 is a horizontal section on the line 4—4 of the Figure 1.

Fig. 5 shows on an enlarged scale the form of 15 the means for raising and lowering of the valve discs.

The knee piece shown in Fig. 1 consists of a casing 1, on the side of which a horizontal pipe branch 2 is provided for connecting the knee piece with the regenerators and below which a vertical pipe branch 3 is provided for connecting 20 the knee piece with the waste gas channel. Opposite to where the pipe branch 2 opens, into the knee piece casing 1, a lean gas pipe branch 4 is connected with which the lean gas pipe line, not shown in the drawings, is also connected. The pipe branch 4 is provided on the inside of the casing with a pipe extension 5 which opens out into the casing above forming a valve seat 6 as can be seen from Fig. 1. In this connection it may be mentioned that the opening of the lean 30 gas pipe extension 5 lies in the casing, as can be seen from Figure 4, on the side near to the opening, and is likewise formed as a valve seat like valve seat 7 of the waste gas pipe branch 3.

The knee piece casing 1 is, moreover, provided 35 opposite the pipe branch 2, with an opening 9 which can be closed by the cover 8 and which permits of the cleaning out of the pipe branch 2 and of the channel connecting with the same and leading to the regenerator and this during the 40 working of the knee piece.

For closing the pipe branches 3 and 4 from the interior of the knee piece casing or the regenerator a pair of double valve discs 10 and 11 serve which can be lowered on the sealing surfaces 6 45 and 7 of the pipe branch openings. The valve disc 10 has in this connection a shaft 13 provided with a tubelike extension 12 which passes through an opening 15 of the casing cover fitted with a labyrinth packing and serves to render the 50 packing more effective. The end of the pipe extension 12 projecting out from the casing has a cap 16 with a thread, through the center hole of which passes the holding rod 17 of a piston piece 18 fitted in the interior of the tube extension 12 and movable in a longitudinal direction. The piston piece 18 is so formed that in its top 55 end position it lies against the inside of the thread cap 16, so that in case of a greater upward movement of the piston rod 17, the pipe extension 12 60 and likewise the valve disc 10 are moved upwards. At its outer projecting end the piston rod 17 is provided further with an eye 19, the importance of which will be explained later.

In a similar manner, as the valve disc 10, the 65 double valve disc 11 is also fitted with a shaft 20 to the upper part of which a pipe extension 21 is connected, which passes through a packing sleeve 22 fitted in the cover of the knee piece casing 1 and carries outside the casing 1 a threaded 70 cap 23. In the interior of the pipe extension there is arranged a movable bearing piston 24, the piston rod 25 of which passes through an opening in the closing cap 23 and bears an eye 26 on the outside.

For moving the two valve discs 10 and 11 there serves a shaft 28 resting on a bearing block 27 fitted on the cover of knee piece casing 1 which supports lever arms 29 and 30 above each of the 5 connecting eyes 19 and 26 of the valve discs 10 and 11. These two lever arms are formed like a sector and have a groove 31 for taking the connecting chain 32, 33, fixed by means of screws 34 and 35 on to the sector levers 29 and 30 respectively. These connecting chains 32 and 33 carry at their free ends hooks 36 and 37 with which they suspend their respective valve shaft eyes 19 and 26.

Furthermore, the working shaft 28 supports 15 still further a lever arm 38 reaching upwards which at the end is shaped in the form of a fork and on which the adjusting rail 50 of the change-over contrivance, not shown in the drawings, grips.

20 The manner of working of the knee piece, shown in the drawings, proceeds approximately in the following manner.

Starting from the position of the valves shown in Figs. 1 and 2. The valve disc 10 is sunk i. e. 25 the lean gas pipe line is shut off, the valve disc 11 is, however, raised i. e. the regenerator is connected up with the waste heat channel. This position of the valves corresponds to the position of the shaft 28 shown in Fig. 2 as well as to the 30 position of the gliding pistons in the tube extensions of the valve shafts shown in Fig. 5. It may be seen from the above named illustrations that in the case of the position of the valves indicated, the piston 18 of the valve disc 10 is in its lower 35 end position so that the valve disc lies closely on the surface of the seat 6, whereas the piston 24 is in its upper end position in which it lies against the shut-off cap 23 of the valve shaft tube extension and, at the same time, the valve disc 11 40 remains above its valve seat in suspension, so that the waste gases from the regenerator through the tube branch 2 may pass over in the branch tube 3 of the knee piece.

If it is intended that the paths taken by the 45 gas in the knee piece be changed over i. e. the lean gas pipe line then is to be connected up with the regenerators which have been preheated by the heat of the waste gases and the waste heat channel is to be closed off against the regenerator, 50 then the working lever 38 of the working shaft 28 is swung over slowly to the right in the position indicated in Fig. 2. In this connection the valve disc 11 is pushed downwards to such an extent that it rests firmly on its sealing surface 7, whereas 55 as at the same time the piston 18 in the pipe extension 12 of the valve disc 10 glides upwards. The tube extension 12 has, in this case, such a length that shortly after the valve disc 11 rests on its sealing surface, the piston 18 impinges 60 on the connecting cap 16 of the pipe extension 12. Consequently when the working lever 38 or in case of the working shaft 28 is further turned round, the valve 10 of the piston 18 is taken along 65 and moved upwards, liberating the opening of the tube extension 5 so that the lean gas can enter into the knee piece and from there pass through the regenerator. During the upward movement 70 of the valve disc 10, the piston 28 in the pipe extension 21 of the valve disc 11 glides downwards. As is seen, the reversing of the direction of the gases closes off, first of all both paths of the gas, before it is possible to obtain the new direction of movement of the gas, especially avoiding any opening of the lean gas pipe line

taking place before the waste heat channel is closed off and, in this way, also preventing the undesirable losses of gas which up to the present 5 has always taken place in the case of lean gas ovens, when the direction of the heating gasses is changed. The knee piece, shown in Figs. 1-5, can also be made use of if the ovens are heated with rich gas. In such a case all the regenerators of the oven serve, as usual, only for the heating of the combustion air and accordingly also all 10 knee pieces must be so arranged that it is possible to suck in the combustion air into the regenerators. For this purpose, there is provided an opening 39 on the cover of the knee piece casing 1 on the side near to the bearing bracket 27 of the 15 working shaft 28, which can be closed by means of a flap 40. The flap 40 is fitted loosely by means of a bolt 21 to a lever 42 which is rested on a projection of the cover 43 of the knee piece casing by means of a bolt 44 with a joint. 20

When making use of the knee piece described above for use in supplying lean gas for lean gas heating, the air flap as already mentioned is closed and secured in its closed position by an adjusting screw 46 gripping on the free 25 somewhat extended end 45 of the lever 42 and threaded through a latch piece 47 which can be turned over. Should, however, the knee piece be utilized for air during heating with rich gas then the safety screw 46 after being loosened from 30 the end 45 of the lever 42 is swung off, so that the lever of the flap can be moved upwards and downwards. Furthermore, the chain 32 may be lifted out of the eye 19 of the shaft of the valve 10 and may be slipped into a hook 48 provided on 35 the lever 42, as indicated in dotted lines in Fig. 2, in such a way that when the working shaft 28 at any time is set in motion, the air flap 40 is opened or closed instead of the valve 10.

The invention as hereinabove set forth is embodied in a particular form of construction, but may be variously embodied within the scope of the claims hereinafter made. 40

I claim:

1. Apparatus for reversing the direction of 45 gases in regenerative ovens comprising: a flow box casing; a gas inlet valve and a waste gas outlet valve therefor within the flow box casing; both valves being actuated by a common mechanism outside the casing; connections between 50 both valves and the actuating mechanism, said connections comprising oppositely movable means outside the flow box casing for effecting the reversal movement of the valves, said connections including for each valve a chain individual thereto and outside the casing and firmly connected to the oppositely movable means and fixed to a lost motion device comprising a piston pull rod slidably guided for limited relative movement within a piston cylinder likewise slidably extending into the interior of the casing through a guiding bushing in the flow box casing and the piston cylinder being fitted to the valve inside the casing whereby the lost motion device is centered by the casing and itself centers the valve inside the casing 55 when actuated by the actuating mechanism outside the casing.

2. Apparatus as claimed in claim 1 and in which the limiting means for the limited relative movement of the piston pull rod relative to the 60 piston cylinder comprises a removable piece fitted on the piston cylinder.

PAUL VAN ACKEREN.
